DISPENSER TOP FOR A PRESSURIZED CAN

James B. Swett, 8 Devonshire Drive, Barrington, R.I.,
and Jack V. Croyle, 159 Spring St., Woonsocket, R.I.

Filed Apr. 3, 1963, Ser. No. 74,284

Term of patent 14 years

(Cl. D58—26)

FIGURE 1 is a perspective view of a dispenser top for a pressurized can showing our new design;
FIGURE 2 is a side elevational view thereof;
FIGURE 3 is a front elevational view thereof;
FIGURE 4 is a top plan view thereof;
FIGURE 5 is a rear elevational view thereof; and,
FIGURE 6 is a cross section taken on line 6—6 of FIGURE 4.
The portions shown in broken lines are for illustrative purposes only.

We claim:
The ornamental design for a dispenser top for a pressurized can, as shown and described.
